UNITED STATES PATENT OFFICE.

ARCHIBALD F. MESTON, OF NEW YORK, N. Y., ASSIGNOR TO RESEARCH CORPORATION, OF NEW YORK, N. Y., A CORPORATION OF NEW YORK.

SYSTEM FOR SCRUBBING COAL GAS.

Application filed December 17, 1918. Serial No. 267,130.

To all whom it may concern:

Be it known that I, ARCHIBALD F. MESTON, a citizen of the United States, residing at New York, in the county of New York and 5 State of New York, have invented certain new and useful Improvements in a System for Scrubbing Coal Gas, of which the following is a specification.

The present invention relates to apparatus for detarring gases and more particularly to apparatus for recovering benzol and ammonia.

It is an object of this invention to provide a system of detarring gases by which the various tarry and associated constituents can be recovered economically, effectively and in 15 a state of comparative purity.

It is the more particular object to provide apparatus for effectively and economically 20 removing ammonia and benzol.

For a fuller understanding of the principles upon which the invention is based, of the mode of operation and the result, reference is had to the accompanying drawings, 25 in which—

Fig. 1 is a diagrammatic representation of a detarring system embodying the invention;

Fig. 2 a sectional view of an absorbing 30 tower forming an essential part of the system shown in Fig. 1;

Fig. 3 a fragmentary sectional view of an electric treater unit employed; and

Fig. 4 a fragmentary view of a detail.

35 The hot tarry gases which come from a retort or coke oven pass through a pipe 1 to a cooling device, preferably a heat exchanger 2 where they are cooled to a temperature at which the water carried is still in vapor form, say slightly above 100° C. The gases thus cooled are then passed into an electric precipitator 3 of the usual or any preferred design where the greater part of the tar is removed while the water remains 40 in the gas. The gases are next passed into a washer 6, a fan 5 being preferably placed into the connecting pipe 4 to force the gas through the system. In the washer 6 the gases are subjected to a spraying device 7 by which they are thoroughly washed and 45 cooled, the excess of water being removed by condensation and entrainment. A cooler in which the cooling agent does not come in contact with the gas has certain advantages 50 and may be substituted for the one shown.

While it is now possible to pass the gases directly to the ammonia scrubber, it is considered best to pass it first through a second electrical precipitator 8 in order to remove all such tar particles that may have escaped 60 the action of the precipitator 3 and have been subsequently condensed by cooling, together with water carried along as mist.

Before going to the ammonia scrubber, the gases are passed through the pipe 9 to the 65 heat exchanger 2 in which they are heated to a temperature of about 50° C. or slightly below. The gases thus reheated pass into the ammonia scrubber 10 and from it to the benzol washer 11 which removes the toluol 70 and benzol. A cooler may be placed between ammonia scrubber 10 and the benzol washer 11 if found advisable.

The ammonia scrubber 10 and the benzol washer 11 are substantially identical in structure and principle of operation. A detail description of one applies therefore equally to the other.

Having now reference to Fig. 2, the device represented includes principally three 80 parts, a chamber containing checker work, a spraying device and an electric precipitator.

The chamber 12 containing the checker-work 13 may be of the usual design. In the spray chamber 14 is disposed a spraying 85 mechanism 15 for discharging absorbent which may be a suitable wash oil. The manner in which and the mechanism by which the absorbent is discharged is not material provided the discharge takes place in the 90 form of a fine mist which is essential for a full realization of the advantages of the invention. There are several reasons for discharging the absorbent in a highly atomized condition or in a fine mist. One is based on 95 the fact that in this condition it presents an enormous absorbing surface to the gas. Another is that mist falling above the checker-work is deposited evenly over it so that a nearly perfect distribution of the absorbent 100 oil through the checkerwork will be realized, which in itself makes for efficient use of the oil and economy. The third and what I consider as the most vital of the reasons is based on the physical properties of a fine 105 mist in contradistinction to an ordinary spray. Highly atomized liquid particles forming a fine mist are easily held in a state of suspension. When exposed to a gas stream they are easily entrained and carried 110

2 along in the stream. The greater part of the fine mist produced in the spraying chamber descends into the passages of the checkerwork, being compelled to do so by the 5 pressure of the successively discharged particles. The gas entering through the inlet 16 and coming up through the passages of the checkerwork passes through the fine mist filling these passages and deposited on the 10 checkerwork with the result that most of the benzol is absorbed in this part of the apparatus. As the gas in a successively purified condition passes up and finally enters the spraying chamber, it is forced to penetrate the fine mist of absorbent liquid just 15 formed and still free of benzol. In passing through the upper zone of the mist the gas stream entrains a considerable quantity of the fine mist particles and carries them upwardly into the electric field of the precipitator 17 immediately above the spraying chamber.

During the upward motion of the fine mist particles, which are at the instant of entrainment entirely free of benzol, the last 25 traces of benzol are absorbed. This process of absorption is greatly facilitated by the action of the electric field which causes, as is well known, a migration of the suspended 30 particles transversely of the gas stream and thereby brings about a thorough mixing with the gases. To this final mixing of the pure absorbent mist with the gases is to a great extent due the complete absorption of 35 the benzol in the gas. In the precipitator 17 the mist is, together with the absorbed benzol, precipitated against the receiving electrodes 17' and the liquid formed flows down the walls thereof into the chamber 40 containing the checkerwork, where it increases appreciably the quantity of absorbent directly received from the spraying chamber. Since this liquid coming from the electrical precipitator 17 is only comparatively 45 slightly charged with benzol, having absorbed only the last traces thereof, it has considerable absorptive capacity and takes the place of a similar quantity of absorbent liquid which would have to be supplied by 50 the spray chamber directly. The saving in absorbent liquid is thereby considerable.

This dual function of the mist entrained by the gas, to first operate to remove those benzol remnants which escape absorption in 55 the checkerwork and in the spray chamber, and then to take part in the function of the checkerwork chamber, is that feature which most characterizes the invention.

While, as before stated, the specific form 60 of mist-forming device is not material to the invention, I found that the arrangement shown in Fig. 4 gives satisfaction when used to dispense viscous liquids which are difficult to spray with ordinary nozzles. The 65 absorbent is passed into the spray chamber

by means of a pipe or pipes 20, controlled by a valve 21 and discharged through nozzles 22. Cleaned gas may be discharged through a nozzle 23 so positioned that the issuing gas stream intercepts the liquid 70 discharged from the nozzles 22. The pressure necessary for the atomization may be produced in the usual manner as for instance by a pressure pump 24.

The electrical precipitator may consist of 75 a plurality of receiving electrode tubes 17' arranged in rows in the usual way. The discharge electrodes 18 are suspended from bus bars 19 which in turn are supported on insulators 25. In order to protect the 80 insulators 25 as much as possible against the effects of a conductive deposit, they are placed under hoods 25' and are mounted in housings 26 substantially isolated from the gas stream.

The tubes 17' have preferably a flaring 85 lower end to which is attached a conical screen 17''. This arrangement has the advantage that it facilitates the mixing of the fine mist particles entrained by the gas 90 stream with the gas and thereby promotes the absorption of the last traces of the gas which have not been absorbed in the absorption chamber or in the spray chamber. The discharge electrodes 18 are preferably 95 rigid so as to maintain their normal position in the tubes 17.

Absorbent liquid may also be supplied, if found desirable, by an auxiliary discharge system 28. There is, of course, considerable 100 latitude as to detail.

As has been previously stated, the ammonia scrubber 10 is similar in every respect to the benzol washer just described. Instead of a wash oil, however, dilute sulphuric acid 105 is atomized to form a mist, as is well known.

The liquid charged with the absorbed benzol and toluol or ammonia respectively is drawn off in the usual way by a liquid-seal drain 27.

It is understood that the invention is not limited to the recovery of ammonia or benzol and toluol from coal gases. It is applicable in all cases where a gas is to be separated from another gas by the use of an 115 absorbent liquid.

While I consider the apparatus shown and described as the preferred embodiment, I am fully aware that, in order to derive the advantages of the invention, the precipitator need not be disposed directly above the spray chamber. The term "above" in the claims is therefore intended to have a broader meaning. It is intended to include all such positions immediately adjacent the 120 spray chamber in which the entrained mist is still carried in suspension by the gas stream and in which it is made possible for the precipitated mist to flow into the absorption chamber and to be distributed therein.

While, as previously stated, the preferred embodiment of the invention includes mechanism for forming a fine mist in order to derive the greatest possible advantage, I 5 consider within the scope of the invention any device for discharging the absorbent liquid by which some mist may be carried along by the gas stream.

In the claims, the term "absorption 10 chamber" is used to define any construction by which a gas stream is brought into intimate contact with an absorbent medium.

I claim:

1. Apparatus for removing a gas from 15 another gas, comprising an absorption chamber, a spray chamber above the absorption chamber and means therein for discharging an absorbent liquid into the absorption chamber as a fine mist, an electric precipitator above the spray chamber, and 20 means for passing the gas stream to be

treated in succession through the absorption chamber, the spray chamber and the electric precipitator.

2. Apparatus for removing a gas from 25 another gas comprising an absorption chamber, a spray chamber above the absorption chamber for distributing an absorbent liquid over the surfaces of the absorption chamber, means in said spray chamber for 30 discharging the absorbent liquid as a cloud or fine mist, an electric precipitator having a plurality of treater units so positioned that the liquid precipitated therein flows down into the absorption chamber and is substantially uniformly distributed therein, and 35 means for passing the gas stream to be treated in succession through the absorption chamber, the cloud and the precipitator.

In testimony whereof I affix my signature.

ARCHIBALD F. MESTON.
